UNITED STATES PATENT OFFICE

PAUL DUGELAY, OF PARIS, FRANCE, ASSIGNOR TO WORTHINGTON PUMP AND MACHINERY CORPORATION, OF NEW YORK, N. Y., A CORPORATION OF VIRGINIA

FEED-WATER HEATER

Application filed November 12, 1927, Serial No. 232,763, and in France December 15, 1926.

This invention relates to feed water heaters and more particularly to feed water heaters of, the open type wherein a heating or condensing chamber is provided into which the water to be heated is sprayed and contacts with incoming steam, preferably the exhaust steam from an engine.

In some heaters of this type, at certain times, the water in the heating or condensing chamber may accidentally rise above the normal level and flow into the inlet pipe for the steam, thereby seriously impairing the operation of the device, and to overcome such impairment of operation the present invention has been devised whereby the flow of water through the inlet pipe will be automatically cut off, at pre-determined times, and any water flowing into the steam inlet pipe will be allowed to drain therefrom, from a point in close proximity to the heater.

More specifically the invention comprehends a valve located in the exhaust steam pipe to the heater, which valve is operated by a piston controlled by the flow of steam to the engine from which the exhaust steam flows to the heater, whereby when the flow of operating steam to the engine is cut off, the valve will be closed, damming the exhaust steam inlet pipe to the heater and a vent or drain will be opened to allow water which might enter the exhaust steam pipe from the heater to drain therefrom. When steam is admitted to the engine, the valve will be opened and the drain closed thereby allowing the exhaust steam to flow unimpeded to the heater.

With these objects in view, the invention consists in various features of construction and combination of parts, which will be first described in connection with the accompanying drawings, showing a feed water heater of the preferred form embodying the invention, and the features forming the invention will be specifically pointed out in the claims.

In the drawings—

Figure 1 is a diagrammatic view of a locomotive showing a feed water heater embodying the present invention applied thereto.

Figure 2 is a section through the steam

pipe to the heater and the mechanism for controlling the flow of steam therethrough and the draining of the pipe.

Referring more particularly to the drawings, an open feed water heater 1 of any approved type is shown mounted on the locomotive 2 and the exhaust steam from the steam engines 3 of the locomotive passes through the steam pipe 4 into the heater 1. The heater 1 is of the open feed water heater type in which the exhaust steam from the engine 3 passes into the heating or condensing chamber 5 into which the water to be heated is pumped by an approved type of pump through the pipe 6. In certain types of these heaters, and at certain times, such as for example when the engine 3 is not working, the water level may rise in the heater, resulting in some of the water flowing into the steam pipe 4 and to prevent such action a valve 10 of any approved construction, but which is shown in the drawings as a butterfly valve is mounted in the steam pipe 4 in close proximity to the heater 1. The butterfly valve 10 is connected by a series of links 11 with a piston rod 12 which is mounted in a cylinder 13. A relatively large piston 14 is mounted upon one end of the piston rod 12 and a relatively small piston 15 is mounted upon the other end of the piston rod. The pipe 4 is provided with an opening 16 between the valve 10 and the feed water heater 1 and this opening 16 opens out into the cylinder 13 and from the cylinder 13 into a drain pipe 17.

A pipe 18 communicates with the end of the cylinder 13 outwardly of the piston 14 and in Figure 1 of the drawings this pipe is shown as going to the cab 8 of the locomotive 2 and to the control 9 which controls the flow of steam to the engine 3 so that when the control 9 is opened to allow steam to flow to the engine 3 of the locomotive 2 steam will also flow through the pipe 18 and into the cylinder 13, forcing the piston 14 against the shoulders 18' and closing the port 19 which establishes communication between the opening 16 and the drain 17. The movement of the piston 14 from against the stop shoulders 20 at the outer end of the cylinder

18, against the shoulders 18' will, through the medium of the links 11 open the valve 10 and allow the exhaust steam from the engine 3 to flow through the pipe 4 into the heater 1.

5 The opposite or small end 22 of the cylinder 13 has a pipe 23 communicating therewith which may receive fluid under boiler pressure or under any other suitable pressure sufficient to move the pistons 15 and 14 when 10 the supply of steam through the pipe 18 is cut off. Upon movement of the pistons 15 and 14 by the fluid entering the reduced end 22 of the cylinder 13, through the pipe 23, the valve 10 will be closed and the piston 14 will be 15 moved away from the shoulders 18' and the port 19 thus opening up the passageway from the steam pipe 4 through the opening 16, cylinder 13, port 19 and drain 17 to permit any water which might flow into the pipe 4 from 20 the heater 1 to drain therefrom.

In the drawings the pistons 14 and 15 are shown of different diameters so as to proportion their active areas in proper relation to the pressures which act upon the respective 25 pistons, to insure efficient operation of the device, however this is a matter of mechanical design and does not form a part of the present invention, the sizes of the pistons being regulated wholly by the relationship between the 30 pressures acting thereon. Also the invention is shown as applied to a locomotive feed water heater but it is to be understood that it is equally applicable for use with other types of feed water heaters wherein steam is supplied 35 from a suitable source to the feed water heater and the valve 10 and draining of the pipe 4 may be controlled by the flow of steam to the source from which steam flows to the heater.

It will be understood that the invention is 40 not to be limited to the specific construction or arrangement of parts shown but that these may be modified widely within the invention defined by the claims.

What is claimed is:

45 1. The combination with a feed water heater having a steam pipe for guiding steam to the heater, of means controlled by the flow of steam to the source from which steam enters said pipe for preventing backward 50 flow of water through the pipe and opening the pipe on the heater side of the valve to permit draining of water therefrom.

2. The combination with a feed water heater having a steam pipe for guiding steam to the heater, of a valve in said pipe, a drain 55 communicating with said pipe on the heater side of the valve, and means controlled by the flow of steam to the source from which steam enters said pipe for operating said 60 valve and controlling said drain.

3. The combination with a feed water heater having a steam pipe for guiding steam to the heater, of a valve in said pipe, a cylinder having communication with the pipe, 65 a piston in said cylinder, a drain communi-

cating with the cylinder and the pipe on the heater side of the valve, said piston operable for operating said valve and for opening and closing said drain.

4. The combination with a feed water 70 heater, a steam engine and a pipe for conducting exhaust steam from the engine to the heater, of a valve in said pipe, and means operated by flow of steam to the engine to open said valve and operated upon the cutting off of steam flow to the engine to close the valve, a drain communicating with said pipe on the heater side of the valve, said means acting to close said drain when said valve is open and open the drain when the 75 valve is closed.

5. The combination with a feed water 80 heater, a steam engine and a pipe for conducting exhaust steam from the engine to the heater, of a valve in said pipe, a piston connected to said valve and adapted to be operated upon the flow of steam to said engine to open said valve and operated upon the cutting off of steam flow to the engine to close the valve, a drain for the part of the pipe between the heater and valve, said piston controlling communication between the drain 85 and steam pipe whereby the drain will be cut off from the steam pipe when said valve is open and will be in communication with the 90 steam pipe when said valve is closed.

In testimony whereof I affix my signature.

PAUL DUGELAY.
